DICE GAME BOX

Donald E. Church, Richmond, Ind., assignor to Avco Corporation, Richmond, Ind.

Filed Dec. 17, 1969, Ser. No. 20,533

Term of patent 14 years

Int. Cl. D21—02

U.S. Cl. D34—5

Fig 1

FIG. 1 is a front perspective view of my dice game box.
FIG. 2 is a top view of such game.

The side opposite the three-spot side in FIG. 1 has the conventional four-spots thereon. The remaining two sides are plain and unornamented.

I claim:

The ornamental design for a dice game box, as shown and described.
